CENTRALIZED TRAFFIC CONTROLLING
SYSTEM FOR RAILROADS

Thomas J. Judge, Rochester, N. Y., assignor to
General Railway Signal Company, Rochester,
N. Y.

Application September 22, 1932, Serial No. 634,374

20 Claims. (Cl. 246—3)

This invention relates to railway centralized traffic controlling systems and more particularly to a system of the non-coded or direct control type, as distinguished from a station selecting type of system.

It is proposed in accordance with the present invention to provide a means for controlling a remote power operated track switch by the polarity of energy applied at the control point to one line circuit, and to control the traffic as well as the direction of traffic over this switch by selectively applying either of two polarities of energy to a second line circuit. It is also proposed to provide means for indicating over these same two line circuits the response of the track switch to the transmitted control therefor, a clear signal and the particular direction which such a signal governs, and the presence of a train on a particular track section. It is further proposed to provide such interlocking of circuits in the communication of controls and indications which will prevent the transmission of conflicting controls and yet which will retain sufficient operating flexibility for the efficient direction of traffic movements.

Other objects, purposes and characteristic features of the invention will appear as the description thereof progresses, in which, reference will be made to the accompanying drawing which illustrates in a diagrammatic and conventional manner one specific embodiment of the present invention which is susceptible of considerable modification or adaptation in practice depending on the type of controls required and the character and number of indications which are considered advantageous in the particular application.

In the accompanying drawing, a complete communicating system is shown for transmitting controls and indications between a typical outlying field station and apparatus associated therewith at a control office. It is to be understood, however, that in a practical application of this system, there will be considerable distance between a field station and the control office, and it is necessary to extend only three line wires over this distance, namely, wires L^1 , L^2 and the wire COM, which wire COM may, if desired, be the common wire for the complete centralized traffic controlling system. In systems having several outlying field stations two line wires such as L^1 and L^2 will of course be required for each such station. The field station apparatus as well as the control office apparatus, as designated by

the legends on the drawing, will also be duplicated for each of the outlying field stations.

A portion of a track diagram which is associated with the typical section of track to which this invention is applied is diagrammatically shown in the accompanying drawing with an indicating light OSI of the conventional type arranged to display an indication of the presence of a train upon a particular section of track and similar indicating lights ESK, WSK, and WSAK, are shown to simulate the actual light signals which govern traffic over the outlying track switch. A signal control lever SGL is employed to set up the controls for wayside signals governing traffic over the track switch, and is operable to three positions, namely, west, stop and east, as indicated by the reference characters W, S and E respectively, and operates suitable contacts which are shown in the conventional manner. A second control lever SML is operable to each of two positions N and R for setting up controls for a switch machine employed to position a track switch in either its normal or reverse operated position.

The section of track corresponding to the portion of track diagram shown at the control office is illustrated at the field station, which section of track includes a track switch TS arranged to route traffic to or from a diverging section of track which may be the entrance of a passing siding and is operated by a switch machine SM which is in turn controlled by a two-position polar relay WZ. Suitable wayside signals ES, WS and WSA are shown in the conventional manner as governing traffic movements over the track switch TS, and the traffic direction is governed by selectively clearing the signals according to the energized position of a three-position polar relay SZ.

Various other relays at both the control office and the field station are shown in the conventional manner and it may be here mentioned that the relay WK at the control office is of the double winding type arranged so that one or the other of these windings is energized depending upon the position of the switch control lever SML and by relatively opposite polarities, but these coils are so connected that the magnetism in the relay remains the same regardless of the polarity of energization and this energization is maintained during a change of position of the lever SML by the overlapping lever contact as shown. The relay SK at the control office is of the three-position polar type, while the relay WLP is of the two-position polar type or is ar-

ranged to retain its last operated position until changed by an energization of the opposite polarity. Other polar and neutral relays at both the control office and the field station have their operating characteristics designated by the base lines thereof, that is the relays having a heavy base line have slower operating characteristics than other relays which are not indicated in this manner.

10 The relay P at the field station is illustrated as being of the type disclosed in the prior patent of O. S. Field, Patent No. 1,969,065, dated August 7, 1934, and it may be here mentioned that this relay when energized operates an armature about a center pivot point in equally time-spaced oscillations to periodically and alternately open and close electrical circuits. It is however desired to be understood that the present system is not limited to the use of such a relay 15 as other arrangements may be substituted, such as two neutral relays having their energizing circuits interlocked to produce alternate operation.

20 In tracing circuits in the description of the operation of the present system, (+) and (−) will be considered opposite extreme terminals of a source of energy at the control office, and also of a similar source of energy located at the typical field station, and (c) will be considered to be 25 a center tap or common potential for these energy sources. It is also to be understood that the common line wire COM is connected to the center tap (c) of both the control office source of energy and the field station source of energy.

30 In the accompanying drawing, the track switch TS is shown in its normal position for routing traffic straight through on the main track, and it will first be considered in describing the operation of the system that the operator desires to 35 reverse this switch for routing traffic upon the passing siding. The switch control lever SML is then moved to position R which reverses the polarity on the switch control relay WZ at the field station over a circuit from (c), through the 40 winding of relay WZ, wire 6, back contact 7 of relay P, front contact 8 of track relay TR, front contact 9 of relay EM, front contact 10 of relay WM, over the line wire L¹, back contact 11 of relay SZP, wires 12 and 13, contact 14 of the 45 lever SML in its reverse position, wire 15, through the upper winding of relay WK to (−).

50 This circuit is effective to shift the contacts of the relay WZ from the right hand position, as shown, to their left or dotted position which is then out of correspondence with the contacts of relay WP thereby closing a circuit to energize the impulsing relay P from (+) contact 16 of relay WP to the right wire 17, contact 18 of relay WZ to the left, wires 19 and 20, through the relay 55 P to (−). Current thus flowing in relay P first flows through coil A and through contact 21 to the left which shunts coil B thus attracting the armature to the right which shunts coil A instead of coil B through contact 21, and this action 60 obviously continues to produce an oscillation of the relay contacts. This operation of relay P then obviously opens and closes the energizing circuit for the relays WZ and WK at equally spaced time intervals but the relay WZ having 65 slow releasing characteristics is not affected by this pulsating energization, but the relay WK at the control office having faster operating characteristics periodically attracts and releases its armature.

70 The relay TK at the control office having slow

releasing characteristics is energized when relay WK is picked up over an obvious circuit completed by front contact 26, but is not dropped when the relay WK momentarily drops. In a similar manner, the relay WKA is picked up 5 during the period in which the relay WK is de-energized over a circuit from (+) back contact 22 of relay SZP, front contact 23 of relay TK, back contact 24 of relay WK, through its operating windings to (−). The relay WKA having 10 slow releasing characteristics similar to the relay TK is not dropped when the relay WK is momentarily energized and consequently a circuit is closed at its front contact 25 to pick up the slow releasing relay WKB in a similar manner but 15 during the period in which the relay WK is energized. In this manner the oscillation of the relay P at the field station is effective to periodically interrupt the switch control circuit which is effective at the control office to pick up the 20 slow releasing relays TK, WKA and WKB thereby closing a circuit to energize the out-of-correspondence light COR over a circuit obvious from the drawing. The indicating light COR may be 25 a miniature lamp placed within the rotary control switch SML so as to be visible from the front of the control panel.

30 During the time that the relay P is operating in the manner to indicate this out-of-correspondence condition, contact 51 of relay WZ being 35 positioned to the left is effective to operate the switch machine SM over the reverse control wire RC in a manner to move the track switch TS to its reverse position. The energizing polarity of relay WP which is connected in the usual manner to repeat the position of the track switch TS is then reversed to operate its contacts into correspondence with relay WZ or contact 16 of relay WP is operated to the left in correspondence with contact 18 of relay WZ to the left. The 40 energizing circuit for relay P is then opened which stops the impulsion of the control line circuit at contact 7 thereby dropping relays WKA and WKB at the control office and extinguishing the out-of-correspondence light COR. A neutral contact 38 is provided on the relay WP which is effective to energize the relay P in the same manner as the out-of-correspondence contacts whenever some abnormal condition prevents the switch TS from assuming its extreme locked 45 position, and obviously the COR light will be 50 energized at the control office in the manner just described.

55 Considering now that the operator desires to allow a train movement from the main track eastward onto the diverging track, the signal control lever SGL is moved to its clear east-bound position E. A circuit is then completed which positions the contacts of the signal control relay SZ to the left, and picks up the series 60 relay SZP at the control office, which circuit may be traced from (c), front contact 28 of relay WP, wire 29, contact 30 of relay WP to the left, wire 31, contact 32 of relay WZ to the left, wire 33, through the windings of relay SZ, wire 34, front contact 35 of relay TR, line wire L² through 65 the upper winding of relay SZP, wire 36, through contact 37 of the signal control lever SGL to the right to (−). The relay SZP picking up 70 opens the circuit for the relay WK at back contact 11, but a stick circuit is then effective to hold up the relay WK from (c), front contact 39 of relay TK, wire 40, front contact 41 of relay SZP, wire 13, contact 14 of the switch control 75

lever SML to the right, wire 15, through the winding of relay WK to (-).

It is obvious that this signal control may have been set up at any time subsequent to the setting up of the new switch control previously traced and yet become effective only after the switch control had been executed. This is because the previously traced switch control circuit immediately operated the switch control 10 relay WZ out of correspondence with the relay WP thereby making the signal control circuit incomplete by the contact 32 of relay WZ being out of correspondence with the contact 30 of relay WP.

15 The series relay SZP at the control office picking up opens the switch control circuit at back contact 11 and shifts the line wire L¹ to include the signal indicating relay SK at the control office. The control circuits for the relays WM and EM are not shown in the accompanying drawing, but it is understood that they are connected in the conventional manner to be selectively de-energized according to the direction in which a clear signal indication is displayed. The circuits for effecting the clearing of the signal ES have been diagrammatically indicated by the dotted line 43 which extends to contact 44 of relay SZ in its left hand position but it is to be understood that this control circuit for the signal ES will include local block signalling circuits which enable a clear signal indication to be displayed only when warranted by the condition of the associated track. Consequently as soon as the signal ES is clear in accordance with the position of the signal control lever SGL, the relay EM is dropped thereby applying energy to the switch control circuit of a polarity which positions the contacts of the relay SK to the right over a circuit from (c), 40 through the windings of relay SK, front contact 11 of relay SZP, line wire L¹, front contact 10 of relay WM, through back contact 9 of relay EM to (-). The signal indicating relay SK now having its contacts positioned to the right in accordance with the clear signal ES at the field station energizes the east bound clear signal indicating means ESK on the control panel from (+), contact 42 of relay SK to the right, wire 45, through the signal indicating means ESK 50 to (-).

The manner in which a west bound signal WS or WSA may be cleared from the control office is obvious from the drawing, or if the signal lever SGL is placed to the clear west bound position W, an opposite polarity is placed upon the line circuit over wire L² which positions the contacts of relay SZ to the right. This position of relay SZ is then effective to clear either of the westbound signals according to the position of the track switch TS and is determined by contact 47 of relay WP which selects either signal WS or WSA as indicated by the dotted lines. It is also obvious that when either signal WS or WSA is cleared, the relay WM drops to apply a polarity of energy to the switch control line circuit or line wire L¹ which positions the contacts of relay SK to the left. With the contacts of relay SK to the left, either the signal indicating means WSK or WSAK is energized depending on the position of contact 48 of relay WLP. The relay WLP is of the two-position polar type and is controlled by contact 49 to repeat the position of the switch control lever SML, but its position may be changed only when the signal 70 indicating relay SK is de-energized because its

energizing circuit includes the de-energized contact 50 of relay SK. The purpose of this arrangement is to prevent shifting of an existing west-bound clear indication from the indicating means WSK to WSAK, or vice versa, by the movement of the switch control lever SML.

A second winding is provided on the relay SZP which is energized by contact 52 of relay SK with a polarity normally corresponding to the polarity of energization on the series or upper winding thereof, and it is evident then that the relay SZP is held up as long as a signal is clear, or in other words, during the existence of a clear signal, a movement of the signal control lever SGL will not drop the relay SZP to extinguish the indication, but such indication will exist until either the relay EM or WM picks up to drop the relay SK at the control office. If some abnormal condition causes an M relay (WM or EM) to drop which does not correspond to the transmitted signal control or the position of lever SGL, the position of the relay SK will not correspond to the position of the lever SGL, and consequently the energization of the lower winding of relay SZP will oppose the energization of the upper winding thereby effecting the dropping of the relay SZP which in turn de-energizes relay SK to allow relay SZP to again pick up. This alternate oscillation of the relays SZP and SK will continue as long as the signal indication is out of correspondence with the signal control, and obviously, the signal indicating light (such as ESK) will be flashed, or alternately energized and de-energized in synchronism with the oscillation of relay SK to indicate this out-of-correspondence condition. 35

Having now described the way in which the track switch TS may be controlled from the control office and the manner in which signal governing movements over this switch may be cleared, it will be considered that a train enters 40 the section of track including the switch TS thereby dropping the relay TR which is a track relay controlled by the conventional track circuit. It is obvious that the dropping of relay TR opens both line wires L¹ and L² at contacts 8 and 35 45 respectively thereby dropping relay SZ at the field station and relay WK at the control office. The dropping of relay WK opens the energizing circuit for the slow releasing relay TK at front contact 26, which relay TK then drops to close a circuit 50 for energizing the track circuit indicating means OSI from (+) back contact 54 of relay WKA, wire 55, back contact 56 of relay TK, through the indicating means OSI to (-).

It will also be obvious that both the east and 55 west bound signals will be at stop when the track relay TR is dropped thereby causing both relays WM and EM to be picked up which drops relay SK to extinguish the existing clear signal indication at contact 42. Relay SZP is also dropped 60 in as much as its upper winding is de-energized at contact 35 of relay TR and its lower winding at contact 52 of relay SK, but relay WK cannot be again picked up with the track relay down because the line wire L¹ is broken at contact 8. 65

A railway centralized traffic controlling system has thus been provided which permits the control of a distant track switch by selecting the polarity of energization of a line circuit including one line wire and a common wire, or, that is, a line 70 wire which may be used as a common potential for the entire system. This line circuit is normally maintained energized with this selected polarity from an energy source at the control point, but when a new switch control is received at the 75

- distant switch location, the circuit is alternately opened and closed for substantially equal periods of time until the switch has been positioned in accordance with the newly transmitted control.
- 5 This interrupted energization is effective at the control office to pick up and hold up certain slow releasing relays which then are effective to energize indicating means to inform the operator that the switch is out of correspondence with the
- 10 position of the switch control lever, but these relays are again dropped when the impulsion is stopped by a proper operation of the switch to thereby extinguish the out-of-correspondence indication.
- 15 The signal governing movements in either direction over the track switch may be selectively cleared by applying either of two polarities of energy to a second line circuit which consists of a second line wire and the previously mentioned 20 common wire. This second line circuit is normally de-energized to effect the displaying of a stop signal for both directions, and includes a series relay at the control office which picks up when a clear signal control is transmitted and 25 shifts the first line circuit from its control office energization to a signal indicating relay. This signal control line circuit also includes correspondence contacts at the field station which requires the position of the track switch to conform 30 with the position of the switch control relay before the selected signal control may be registered. When a clear signal is displayed, an indication is transmitted to the aforesaid signal indicating relay at the control office by energizing the first 35 mentioned line circuit at the field station with a polarity which is distinctive of the particular traffic direction which the clear signal governs. One feature of the signal indicating means is that a movement of the signal control 40 lever from a clear to a stop position is not directly effective to extinguish the clear indication, but that the indication is only extinguished by removing the field station energy from the line circuit. Another feature of the signal indicating 45 means is the provision against incorrectly changing an existing indication of one clear signal to another signal by a movement of the switch control lever.
- A means for indicating the presence of a train 50 on a track section associated with the distant track switch has also been provided by opening both the previously mentioned line circuits at the field station due to the dropping of a conventionally arranged track relay, which de-energization 55 is effective to drop a slow releasing relay at the control office thereby energizing a track section indicating means. It will be noticed that intermittently both of these line circuits are de-energized during the transmission of an out-of-correspondence switch position but such de-energized periods are arranged to exist for a shorter time than is effective to drop the aforesaid slow releasing relay.
- The above rather specific description of one 60 form of the present invention is given solely by the way of example, and is not intended, in any manner whatsoever, in a limiting sense. It is also to be understood that various modifications, adaptations and alterations may be applied to 65 meet the requirements of practice, without in any manner departing from the spirit or scope of the present invention, except as limited by the appended claims.

Having thus described my invention, what I 75 claim is:—

1. In a railway traffic controlling system, a control office, a distant track switch and associated directional signals, two line circuits connecting the control office and the track switch and signals, a two-position control relay associated with said track switch and selectively operable to either position according to the polarity of energy applied to the first of said line circuits, contact oscillating means arranged to alternately open and close said first line circuit whenever the position of said control relay is out of correspondence with the position of said track switch, means at the control office responsive to the opening and closing of said first line circuit to indicate said out-of-correspondence condition, 15 and means for selectively clearing said signals in either direction in accordance with the polarity of energy applied to the other of said two line circuits only when said two-position control relay is in a position corresponding to the position of 20 said track switch.
2. In a railway traffic controlling system, a control office, a distant field station, a first line circuit connecting the control office and the field station, a track switch control means at the field 25 station positioned according to the polarity of energy applied at the control office to said first line circuit, means for indicating at the control office an out-of-correspondence condition between the track switch and said control means by alternately opening and closing said first line circuit, a second line circuit connecting the control office and the field station, signal control means at the field station governed by the energization 30 of said second line circuit, and means for indicating a clear signal condition at the control office by energy applied at the field station to said first line circuit.
3. In a railway traffic controlling system, a control office, a distant field station, a first line 40 circuit connecting the control office and the field station, a track switch control means at the field station positioned according to the polarity of energy applied at the control office to said first line circuit, means for indicating at the 45 control office an out-of-correspondence condition between the track switch and said control means by alternately opening and closing said first line circuit, a second line circuit connecting the control office and the field station, signal control 50 means arranged to selectively clear traffic signals in either direction according to the polarity of energization of said second line circuit, and means for indicating a clear signal condition at the control office by energy applied at the field 55 station to said first line circuit.
4. In a railway traffic controlling system, a control office, a distant field station, a first line circuit connecting the control office and the field station, a track switch control means at the field 60 station positioned according to the polarity of energy applied at the control office to said first line circuit, means for indicating at the control office an out-of-correspondence condition between the track switch and said control means by alternately opening and closing said first line circuit, a second line circuit connecting the control office and the field station, signal control means arranged to selectively clear traffic signals in either direction according to the polarity of energization 65 of said second line circuit, and means for indicating the governing direction of a clear signal condition by the polarity of energy applied to said first line circuit.
5. In a railway traffic controlling system, a 75

control office, a field station, a normally energized line circuit connecting the control office and the field station, means for controlling a track switch at said field station according to the 5 polarity of energization of said line circuit, an oscillating contact means at said field station operable to impulse said line circuit when the position of said track switch does not correspond to the polarity of said line circuit energization, 10 means at the control office responsive to impulsive energization of said line circuit, a second line circuit connecting the control office and the field station, means at the field station arranged to de-energize said normally energized line circuit and 15 said second line circuit when a train occupies a particular track section, and means at the control office distinctly responsive to the said de-energization of said line circuits.

6. In combination, a control office, a field station, a first line circuit connecting the control office and the field station, means for controlling a track switch at the field station by energizing said first line circuit, a second line circuit connecting the control office and the field station, 20 means for clearing a signal at the field station by energizing said second line circuit at the control office, a signal indicating means at said central office, means for initially connecting said first line circuit to said signal indicating means 25 at the control office only when said second line circuit is energized and thereby deenergizing said first line circuit, and means for energizing said first line circuit at the field station when said signal is clear.

30 7. In combination, a control office, a field station, a first line circuit connecting the control office and the field station, means for controlling a track switch at the field station over said first line circuit, a second line circuit connecting the control office and the field station, means for 35 clearing either of two signals at the field station by selecting the polarity of energization of said second line circuit at the control office, a signal indicating means at said control office, means for initially connecting said first line circuit to said signal indicating means at the control office only when said second line circuit is energized, and means for energizing said first line circuit at the field station with one polarity or another 40 depending upon which of the two signals is cleared.

45 8. In combination, a control office, a field station, a first line circuit connecting the control office and the field station, means for controlling a track switch at the field station over said first line circuit, a second line circuit connecting the control office and the field station, means for clearing either of two signals at the field station by selecting the polarity of energization of said 50 second line circuit at the control office, means for connecting said first line circuit to a signal indicating means at the control office when said second line circuit is energized, and means for energizing said first line circuit with a distinctive polarity when one of said signals is clear, and 55 means for de-energizing said first and said second line circuits to indicate at the control office an occupied condition of a track section at the field station.

60 9. In combination, a track switch, a control lever for said track switch, a switch control relay, a switch control circuit arranged to position said switch control relay in accordance with the 65 position of said switch control lever, an oscillating relay arranged to periodically open and close 70

said switch control circuit when the position of said switch control relay is out of correspondence with the position of said track switch, a first slow releasing relay arranged to hold up during the periodic opening and closing of said switch 5 control circuit, a second relay arranged to pick up during the periodic opening of said control circuit providing said first relay is picked up and to hold up during the periodic closing thereof, a third relay arranged to pick up during the 10 periodic closing of said line circuit providing said first and second relays are picked up and to hold up during the periodic opening thereof, and an indicating means energized when said first, second and third relays are picked up. 15

10. In combination, a track switch, a control lever for said track switch, a switch control relay, a switch control circuit arranged to position said switch control relay in accordance with the position of said switch control lever, an oscillating relay arranged to periodically open and close 20 said switch control circuit when the position of said switch control relay is out of correspondence with the position of said track switch, a first slow releasing relay arranged to hold up during the periodic opening and closing of said switch control circuit, a second relay arranged to pick up during the periodic opening of said control circuit providing said first relay is picked up and to hold up during the periodic closing thereof, 25 a third relay arranged to pick up during the periodic closing of said line circuit providing said first and second relays are picked up and to hold up during the periodic opening thereof, an indicating means energized when said first, second 30 and third relays are picked up, means for continuously opening said switch control circuit during the presence of a train on said track switch, and a second indicating means responsive to said continuous opening of said switch control circuit. 35

11. In combination, a track switch, directional signals associated with the track switch, a switch control relay, a control circuit for said switch control relay, a signal control relay, a normally de-energized control circuit for said signal control relay, means for positioning said signal control relay by selecting the polarity of energization of said signal control circuit, a relay arranged to connect said switch control circuit to a signal indicating relay when said signal control circuit 40 is energized, and means for applying energy to said switch control circuit of a polarity determined by the governing direction of a clear signal to thereby position said signal indicating means. 45

12. In combination; a control location; a distant traffic controlling device; a line circuit connecting the control location and the distant traffic controlling device; a control lever at the control location effective to energize said line circuit with opposite polarities of current; a polarized relay at the traffic controlling device, said polarized relay being included in said polarized line circuit and caused to assume opposite positions depending upon the polarity of the current applied to said line circuit by said control lever; 50 indication transmitting means for at times opening and closing said line circuit periodically in accordance with said traffic controlling device; indication receiving means at the control location so constructed and included in said line circuit 55 and associated with said control lever as to be responsive to the periodical opening and closing of said line circuit by said indication transmitting means but to be unaffected by a reversal of the polarity of said line circuit, which reversal 60

is relatively quicker than said periodical opening and closing; and indication means controlled by said indication receiving means.

13. In combination; a track switch; a polar relay for controlling said track switch; a control lever; a source of current; a line circuit for energizing said polar relay with one polarity or the other from said source of current depending upon the position of said lever; a double wound indication relay having one winding or the other included in said line circuit depending upon the position of said control lever to thereby respond to the open or closed condition of said line circuit but to be unresponsive to a change in the polarity of current in said line circuit; an oscillating relay arranged to periodically open said line circuit when the position of said polar relay is out of correspondence with said track switch; other means for at times steadily opening said line circuit; and indication means controlled by said double wound indication relay so as to give distinctive indications in accordance with whether said indication control relay is steadily energized, steadily deenergized, or periodically deenergized; whereby the operation of said control lever does not effect said indication means.

14. In combination, a track switch and signals for governing traffic thereover, a control lever for governing said track switch, indication means for indicating when said signals are cleared or at stop, a relay capable of being positioned in accordance with said lever only while said indication means indicates stop, and indicator means distinctively controlled by said relay only when said indication means indicates that said signals are cleared.

15. In a traffic controlling system for railroads; a track switch and signals for governing traffic thereover; a switch machine for operating said track switch; control relay means for governing the operation of said switch machine; a control lever; a line circuit connecting said control lever and said control relay means, whereby the manipulation of said control lever governs said control relay means; signal control relay means for governing the clear and stop indications of said signals; a signal control lever; a line circuit connecting said signal control lever and said signal control relay means, which line circuit is energized whenever said signals are to indicate clear; indication means for indicating when said signals indicate clear, when rendered effective; a relay picked up whenever said signal control line circuit is energized; means opening said switch control line circuit and rendering effective said indication means when said relay is picked up; and means energizing said relay independently of said signal control line circuit so long as said indication means indicates clear; whereby said switch control lever is rendered ineffective once a signal is clear until that signal indicates stop independently of said signal control lever.

16. In combination, a line circuit connecting two spaced locations; means for at times applying energy to said line circuit from one of said locations and at other times from the other of said locations; means at said other location for impressing any one of a plurality of distinctive conditions on said line circuit, said conditions including a steady energization of one polarity or the other when energy is applied to said line circuit from said other location, and said conditions including a steady energization, a steady deenergization, or an intermittent deenergization when energy is applied to said line circuit from

said one location; means at said other location for determining which particular distinctive condition is to be impressed on said line circuit; and means at said one location controlled in accordance with the distinctive conditions impressed on said line circuit.

17. In combination, two spaced locations interconnected by two line wires, a source of energy at one of said locations and provided with a mid-tap connected to one of said line wires, an indication relay having two windings, control means for connecting either one terminal of said source to the other of said two line wires in series with one of said windings in one relationship or the other terminal of said source to said other of said two line wires in series with the other of said windings in an opposite relationship and said control means being capable of shifting from one terminal to the other without deenergizing said relay, a polar relay at the other of said locations for controlling a traffic device and being included in the line circuit formed by said two line wires, means for at times opening the line circuit formed by said two line wires to thereby deenergize said indication relay, and other means controlled by said indication relay.

18. In combination; a line circuit connecting a control office and a distant traffic controlling device; a control lever at the control office for energizing said line circuit with positive or negative energy; transmitting means at said traffic controlling device capable of periodically opening and closing said line circuit, when said transmitting means is energized; a polar relay included in series in said line circuit for controlling said traffic controlling device, the contacts of said polar relay being responsive to a change in the polarity of the energy applied to said line circuit but being unresponsive to said periodic opening and closing of said line circuit by said transmitting means; a neutral relay having windings; means so connecting said windings of said neutral relay in said line circuit by said control lever that the reversal of the polarity of the energy applied to said line circuit by said control lever maintains the same direction of magnetic flux in said relay; whereby the contacts of said relay are unresponsive to a reversal of the polarity of the energy applied by said control lever but are responsive to said periodic opening and closing of said line circuit by said transmitting means; indication means controlled by said neutral relay; and means at said traffic controlling device for at times energizing said transmitting means in accordance with the condition of said traffic controlling device.

19. In combination; a line circuit connecting a control office and a distant traffic controlling device; a control lever at the control office for energizing said line circuit with current of one polarity or the other; transmitting means at said traffic controlling device capable of periodically opening and closing said line circuit, when said transmitting means is set into operation; a polar relay included in series in said line circuit for controlling said traffic controlling device, the contacts of said polar relay being responsive to a change in the polarity of energy applied to said line circuit but unresponsive to said periodical opening and closing of said line circuit by said transmitting means; a neutral relay; means for causing said neutral relay to be picked up whenever steady current flows in said line circuit and to remain picked up upon a reversal of the polarity of current in said line circuit by said

control lever but to be dropped away whenever said line circuit is periodically opened by said transmitting means or whenever said line circuit is steadily deenergized; indication means controlled by said neutral relay and capable of giving a distinctive indication in accordance with the steady energization, periodical opening, or steady deenergization of said line circuit; means at said traffic controlling device for at times setting said transmitting means into operation in accordance with the condition of said traffic controlling device; and means for at times steadily deenergizing said line circuit in accordance with traffic conditions.

15 20. In combination; a line circuit connecting a control office and a distant traffic controlling device; a control lever at the control office for energizing said line circuit with positive or negative energy; transmitting means at said traffic controlling device operable to periodically open and close said line circuit when said transmitting means is energized; a slow acting polarized relay included in series in said line circuit for govern-

ing said traffic controlling device, the contacts of said polarized relay being responsive to a change in the polarity of the energy applied to said line circuit but unresponsive to said periodic opening and closing of said line circuit by said transmitting means because of the slow acting characteristics of said polar relay; a neutral relay having two windings; means so connecting said two windings of said neutral relay in said line circuit by said control lever that the reversal of the polarity of the energy applied to said line circuit by said control lever maintains the same direction of magnetic flux in said neutral relay, whereby the contacts of said neutral relay are unresponsive to a reversal of the polarity of the energy applied by said control lever but are responsive to said periodic opening and closing of said line circuit by said transmitting means; indication means controlled by said neutral relay; and means at said traffic controlling device for at 20 times energizing said transmitting means.
